Long Island City, N.Y., a corporation of New York

Application November 28, 1955, Serial No. 549,406

8 Claims. (Cl. 1—3).

This invention is a stapling machine having a swingable staple containing arm hingedly associated with an anvil carrying base and adapted to be conveniently swung to the rear of the base to permit the stapling machine to be employed as a tacker. One object of the invention resides in the provision of a one piece open top, open bottom and open rear magazine having normally diverged and transversely spaced sides integrally merged with and interconnected at their front ends only by a transversely disposed front wall whereby these sides upon the application of outside finger pressure thereon are readily moved, that is, flexed towards each other relative to the front wall to permit the reception within the magazine of a staple pusher having means for interlocking with transversely spaced staple guiding rails carried by the sides and interposed therebetween to limit divergence of and to retain the sides and the rails in substantial parallelism upon removal of the finger pressure formerly applied to the sides preparatory to mounting the magazine on the base. Another object is realized in the provision of a fixed stanchion rising upwardly from the rear of the base and adapted to be conveniently assembled therewith and including transversely spaced ears having aligned openings for supporting fulcrum means swingably carrying both the magazine and the cap. Another object resides in interlocking the rear end of the stanchion with the rear part of the base and subsequently interlocking the front end of the anvil carrying member with the front end of the base and thereafter superimposing the anvil carrying member on a forwardly extending plate of the stanchion whereby this plate and the anvil carrying member are thereafter anchored together by rivet means to the base. Another object is to employ the fixed stanchion whereby it can be straddled by transversely spaced corresponding rear ends of the sides of the magazine and thus serve as stabilizing means for the magazine, that is, to provide rigidity in precluding squeezing of such sides towards each other. Another object is realized in employing a resilient upstanding and biased loop extending upwardly and rearwardly from the rear end of the anvil carrying member for normally holding the swingable arm spaced from the fixed anvil carrying member. Another object is to provide spaced wings integral with and rising upwardly from the base for movably guiding the swingable arm during its swingable displacement towards or away from the fixed anvil carrying member. Another object is to provide depending legs at the rear of the spaced sides of the magazine to removably straddle transversely spaced ears of the fixed stanchion and having aligned openings including walls adapted to snap by and thereafter be removably but loosely interlocked with overhanging detents struck out of and laterally extending of the spaced ears. Another object is concerned with staple driving means in the form of a one piece flat spring having an offset rear tail portion anchored to the cover or cover plate, the latter also slidably guiding displacement of the driving blade and additionally acts to fairly close the top wall of the magazine, the one piece spring

2

having an arcuate intermediate part sloping upwardly and forwardly away from the tail portion and including a substantially horizontal reach from which the driving blade depends, the arrangement being such that the horizontal reach of the flat driving spring is appropriately secured against the top wall of the cap while the arcuate portion of the driving spring includes a depending lug for retaining the upper terminal of a normally contracted helical spring trained about a sheave appropriately anchored to the cover while the lower terminal of the normally contracted spring is retained by the slidable pusher guided by the magazine whereby if the cap be swung towards the magazine, the pusher automatically advances towards the front wall of the magazine and if the cap be swung away from the magazine to open the latter the pusher automatically moves towards the rear of the magazine.

Other important objects, and functional and structural features of the invention will be apparent from the following detailed description taken with the accompanying drawings wherein:

Fig. 1 is a side elevational view of the stapling machine.

Fig. 16 is a plan view of Fig. 14.
Fig. 17 is a bottom view of Fig. 14.

Fig. 18 is a fragmentary perspective view illustrating the cover of the carrier slightly raised from the magazine.

Fig. 19 is a view similar to Fig. 18 showing the cover within and closed relative to the magazine at which time the cover at its front end is nested within the upper rim of the magazine.

Fig. 20 is an exploded perspective view of the magazine and staple pusher, and illustrating the normally diverged relation of the sides of the magazine.

Fig. 21 is a plan view showing the manner of flexing the magazine sides towards each other on mounting the staple pusher therein.

According to the invention, the stapling machine generally designated SM comprises an effective base B, pivotally supporting the swingable staple carrying arm broadly denoted SA. Base B is preferably of sheet metal, appropriately depressed centrally thereof to provide an intermediate arranged wall 10 which includes the centrally arranged boss or seat 11 extending above the elevation of front end 12 and rear part 13 thereof.

Integral with and projecting above wall 10 are the spaced ribs 14. Interconnecting the front ends of ribs 14 is lip 15 which extends above and is spaced from the front depressed end 12 of the intermediate wall 10 and forms therewith gap 16 (Fig. 11).

Extending rearwardly of rear part 13 of wall 10 and integral therewith is a reduced web 17 (Fig. 10) which is upwardly offset and merges with the rearwardly flared part 18 integral with the rear end of base B.

Transversely spaced and upstanding flanges or wings 19 are integral with the body of the base B and are in longitudinal alignment with the spaced ribs 14.

Web 17 and flared part 18 are appreciably spaced from the bottom parts of the upstanding flanges 19 and form the spaced openings 29. For strengthening purposes flanges 19 are each provided with an outwardly extending boss or hollow rib 21.

Base B carries the fulcrum support or stanchion, broadly designated FS (Fig. 10), which is formed out of a one piece sheet metal member comprising rear wall 22 having the upwardly and forwardly curved crown portion 23 against which the transversely spaced ears 24 of stanchion FS are arranged. Depending from crown portion 23 is the downwardly and forwardly inclined web 25 merging with the biased shoulders or lips 26 extending upwardly and rearwardly from flat plate 27.

Reduced web 17 and the flared part 18 of the base B may be considered as an offset brace interconnecting rear part of depressed portion 13 with the rear part of rim RR and defines in part the spaced openings or relief passageways 29.

Interrupting the rear part of base B near flared part 13 is the positioning slot 28 which receives a substantially corresponding cross sectionally shaped lug 29. Thereafter hanger or stanchion FS is rotated downwardly whereby the locating dimple or projection 30 extending from rear part 13 of the bottom wall 10 of base is automatically received in the hollow bottom dimple or projection 31 of flat plate 27 of the hanger FS. In such relation, plate 27 is also automatically positioned and received within recess R formed by spaced ribs 14 and rear part or seat 13 of the bottom wall 10 of the base. Thereafter lug 29 which is substantially normal to rear wall 22 of hanger FS is appropriately spot welded to the base. By this arrangement, stanchion FS is positioned on, interlocked with and effectively anchored to the base.

Subsequently the anvil carrying plate, broadly designated, AC is assembled with and secured to base B. In this connection, it will be observed that plate AC is provided at its front end with depending downwardly sloping tongue 32 which is inserted into slot 16 under lip 15 of the base. Plate AC in width is substantially commensurate with the distance between spaced ribs 14. Consequently these ribs automatically position plate AC when the latter is swung downwardly towards wall 10, and by such action opening 33 of ear 34 towards the rear of plate AC is automatically received by the positioning dimple 31 projecting upwardly from the flat plate 27 of stanchion FS. Thereafter an appropriate rivet 35 passing through anvil plate AC, plate 27 of stanchion FS, and bottom wall 13 of the base, effectively anchors these parts together. As is well understood, anvil plate AC at its front end is provided with an appropriate indented part 40 adapted to clinch the legs of the foremost staple S of a staple stack SS (Fig. 11) as it is driven out of the stapling machine.

Before specifically discussing the structure of the swingable arm SA, it may be well to mention at this time that after the swingable arm SA is completely assembled, and the base B has been completely assembled with its stanchion FS and anvil carrier plate AC, the arm SA which includes cap C may now be readily and swingably mounted on stanchion or hanger FS as desired. To this end, it will be noted that alined openings 41 (Figs. 11A, 26) interrupt the rear ends of the spaced sides 42 of

magazine M and from these sides 42 (Figs. 11A and 11B) the spaced legs 44 depend. Legs 44 are provided with alined openings 45 (Fig. 11). Sides 42 and legs 44 of magazine M are adapted to rotatably straddle and embrace the transversely spaced ears 24 of stanchion FS. Ears 24 are interrupted by the alined openings 46.

Spaced ears 47 of cap C also rotatably straddle and embrace the spaced sides 42 of the magazine. Ears 47 of cap C include alined openings 48 (Figs. 9 and 13) adapted to line up with the spaced openings 41 in sides 42 of magazine M and openings 41 are in alignment with the spaced openings 46 in ears 24 of stanchion FS. It follows that fulcrum pin FP may be conveniently inserted through alined openings 48 of the cap, the alined openings 41 of magazine M, and the alined openings 46 of stanchion or fulcrum support FS and thereafter appropriately upset to swingably retain the magazine M relative to the base B and cap C swingable relative to magazine M, that is, arm SA may be swung to the position shown in Fig. 7 or the cap C may be swung rearwardly to fully open the magazine M as shown in Figs. 5 and 6 at which time full access may be had to the staple receiving channel formed by the magazine M as is well appreciated.

Normally arm SA is in the position shown in Fig. 11, that is, magazine M is seated on the spring loop L which is integral with and extends upwardly and rearwardly away from the sheet metal anvil carrying plate AC. By this action, magazine M is resiliently urged away from base B. Also in this relationship dimples or detents 50 of ears 24 of stanchion FS are within openings 45 in the spaced legs 44 of magazine M, that is, dimples 50 are removably interlocked within walls of openings 45 which are slightly larger than dimples 50 to permit pivotal downward displacement of arm SA although cooperating with walls of openings 45 to limit upward swingable and rearward displacement of the magazine to its normal position shown in Fig. 11. During pivotal displacement of the magazine M, the upstanding flanges 19 of base B serves as supplementary means to guide such displacement.

Magazine M is formed out of a single piece of sheet metal and comprises the front wall 51 and the spaced sides 42. Merged with and interconnecting sides 42 with the front wall 51 are the rabbeted portions 52 comprising spaced shoulders 53 extending laterally of front wall 51 which preferably includes at the upper end the upwardly forwardly sloping lip 54. Within magazine M and spaced from and substantially parallel to the spaced sides 42 are the transversely spaced rails or upstanding flanges 55 which support the U shaped stack of staples SS. Each rail 55 at its bottom is merged with and connected to an adjacent side 42 by a web 56. At their forward ends the upstanding rails 55 extend beyond webs 56 and towards but spaced from the inside surface of front wall 51 to form therewith spaced gaps 57 forming staple guide means or a raceway below the slotted staple driving blade DP depending from reach 58 of the compressible and flat spring generally denoted DS having a downwardly and rearwardly sloping intermediate arcuate or bowed portion 59 from which rearwardly extends the flat terminal 60 fastened by rivet 61 to tail portion 62 of the cover or cover plate CP for magazine M. Tail portion 62 is offset relative to and extends above the intermediate part of cover CP.

Blade DB includes slot 63 receiving reduced neck 64 from which extends the laterally projecting lug 65. Spaced portions 66 of blade DB movably straddle neck 64. Normally the flat compressible spring DS is in its raised position shown in Figs. 11, 14 and 15. The lower part 67 of slot 63 (Fig. 15) is contracted and the lower wall thereof cooperates with neck 64 to limit upward displacement of blade DB. Lip 68 (Figs. 11 and 14) at the front part of cover plate CP also guides displacement of blade DB which is further movably guided between the spaced lugs 69 (Fig. 12) projecting from flange 70 which carries neck 64. Flange 70 (Fig. 14) is substantially

normal to and integral with the spaced lugs or depending portions 71 (Fig. 15) bent up from the front part of cover plate or cover CP having the elongated centrally arranged slot 72. Cap C is anchored fixedly to reach 58 of depressible spring DS by the bent lugs 73' and 73 depending from top wall 74 of cap C which is of sheet metal and hollow having its front wall 75 spaced from and disposed forwardly of the laterally extending or T shaped lug 65 of cover CP.

The forward parts 76 of the spaced sides 77 of the cap however are spaced from sides 42 of magazine M while the rear portions 78 of sides 77 closely but movably fit over sides 42 of the magazine. Ears 47 previously referred to extend from the rear portions 78 of cap C. By the arrangement disclosed, cap C carries bodily both depressible spring DS and cover CP but the cap C through the perforated ears 47 is also swingable relative to fulcrum pin FP.

Referring back to magazine M, webs 56 and the rails 55 are interrupted by the spaced guide slots 79 which receive the inwardly turned lugs 80 of depending sides 81 of the staple pusher P slidably guided by and straddling the spaced rails 55 which are disconnected from each other.

Extending from pusher P is the hook H (Fig. 11) retaining loop 83 at the lower reach 84 of the helical normally contracted spring 85 threaded through slot 72 of cover CP and having its intermediate portion trained over the fixed coiled sheave 86. The upper reach of spring 85 has its terminal loop 87 retained by hook 88 depending from arcuate intermediate part 59 of the depressible spring DS. If therefore cap C be actuated, that is, swung back and forth, the slidably guided and staple pusher P will be reciprocated relative to the spaced rails 55 of magazine M.

As previously stated the front parts of the spaced sides 42 of the staple magazine are interconnected with the front wall 51 by reason of the rabbeted portions 52. The rear ends of sides 42 however are free and disconnected from each other (Fig. 21). Thus due to the resiliency of the sheet metal out of which the magazine is formed, the spaced sides 42 (Fig. 20) of the magazine are normally diverged. These sides, however, may be brought towards each other as shown in Fig. 21, that is, swung or flexed relative to the front wall 51 at which time pusher P is dropped into the magazine to straddle rails 55 whereupon lugs 80 of pusher P fall within slots 79 and under the spaced rails 55. Subsequently the finger pressure applied to bring the sides 42 of the magazine towards each other is removed and sides of the magazine automatically spring outwardly but such outward displacement is limited or restrained by the spaced sides 81 of pusher P which holds the spaced rails 55 against further spreading and consequently sides 42 are set a predetermined distance apart (Fig. 22) for reception of the staple stack SS. Rails 55 are each reinforced by a suitable longitudinally arranged rib 82.

Slots 79 which interrupt spaced webs 56 and rails 55 have end walls cooperating respectively with the inwardly turned lugs 80 to limit forward and rearward displacement of slidably guided staple pusher P.

Sheave 86 is formed out of a wire comprising a plurality of juxtapositioned coils progressively increasing in diameter away from the central coils thereof and consequently defining a groove for appropriately receiving the helical spring 85 which urges staple pusher P forwardly when the cover is closed and consequently staple stack SS is urged towards the front part of magazine M. The end coils of sheave 86 terminate in ends 92 spot welded to front spaced portions of the cover CP.

Cover CP is a supporting plate for the depressible staple driving spring DS and is limited in its downward swingable displacement by the spaced shoulders 53 at the rear and disposed laterally of front wall 51 of magazine M, that is, shoulders 53 of rabbeted corner portions 54

serve as a stop means coacting with flange 70 of cover CP to limit such downward movement of cover CP at which time spaced lugs 93 bent inwardly from the spaced sides 42 of the magazine support the rear end or tail piece 62 of cover CP. This relation is clearly shown in Fig. 11 wherein also cover CP is slightly above the staple strip or stack SS to prevent upward displacement of the latter, namely, to facilitate guiding and to hold such strip on the spaced rails 55. With cover CP resting against stop flanges or shoulders 53 and supported by lugs 93, the cover "closes" the open top of magazine, that is, spaced bars 110 thereof constituting the bottom of the cover are within the magazine but slightly above the staple stack SS to hold the latter on rails 55.

To permit the normally raised cap C to be depressed relative to both magazine M and cover CP when the latter is supported by lip 54 and the inwardly overhanging lugs 93 of the magazine, sides 42 of the magazine are provided with relatively large and transversely aligned perforations 94 adapted to removably receive inwardly struck detents or dimples 95 extending from the rear parts 78 of the spaced sides 77 of cap C.

On closing of the pivoted or hinged cap C, dimples 95 frictionally but movably straddle sides 42 of the magazine and eventually snap into aligned perforations 94 to loosely interlock therewith, that is, also to removably interlock therewith. To open cap C, that latter is grasped and swung upwardly, thus automatically removing dimples 95 from perforations 94. If cap C be swung open, driving spring DS and cover CP bodily swing back therewith to provide full access to the staple receiving channel constituted by front wall 51, side walls 42, webs 56 and spaced rails 55 of magazine M.

As already pointed out, the stapling machine may be readily converted into a tacker. This is accomplished by grasping swingable arm SA and swinging the latter rearwardly of the base to the position shown in Fig. 7. By such action legs 44 of spaced sides 42 of magazine M unlock from detents 50 of stanchion FS which serves as an abutment cooperating with rear end 96 (Fig. 7) of top wall 74 of cap C to restrict rearward swingable displacement of cap C.

With the present invention, the carrier which comprises cover CP and spring DS, may be readily assembled with cap C. In this connection it will be noted that slot 63 interrupting blade DB is adapted to conveniently receive the biased lug 73' extending downwardly from cap C, thereby automatically positioning cap C relative to spring DS after which lug 73 is projected through opening 97 interrupting reach 58. Thereafter lug 73 is bent upwardly and against the bottom face of reach 58 to firmly secure spring DS to cap C. Lug 73' may be considered also as a stop against which reach 58 is maintained.

Prior to inserting and upsetting rivet 61 and to facilitate assembling of the depressible driving spring DS with cover plate CP, tail 60 (Fig. 11) of spring DS includes locating opening 100 for closely receiving the cooperating dimple 101 extending from terminal or tail 62 of cover plate CP.

By applying a downwardly directed manual pressure on cap C, arm SA swings downwardly against the resistance of spring loop L and blade DB drives the foremost staple out of raceway defined by spaced gaps 57 and against the indented portion 40 of anvil AC. Of course during downward pivotal displacement of cap C, spring DS is stressed. After the foremost staple has been driven out of the magazine and clinched against the anvil, the downward directed manual pressure formerly applied to the cap is removed. Automatically thereafter loop L elevates magazine M and spring DS elevates blade DB and cap C. Upward swingable displacement of magazine M is limited by the spaced dimples or stop means 50 of stanchion FS. These dimples coact with the lower portions of the relatively large openings 45 to limit such

upward displacement. Openings 45 also removably interlock with the dimples 59 to hold depending legs 44 of the magazine in movable straddling relation to the inwardly bent ears 24 of stanchion or fulcrum support FS.

Various changes may be made in details of construction and arrangement of parts without departing from the scope of the invention or sacrificing any of the advantages inherent therein.

I claim:

1. In a stapling machine, a one piece sheet metal magazine adapted to contain staples and provided with a front wall, spaced sides having front ends integrally merged with and normally yieldingly diverging away from said front wall, spaced webs disconnected from each other and integral with the lower portions of said sides and spaced from said front wall, spaced upstanding rails disconnected from each other and spaced from said front wall and substantially parallel to and spaced from said sides and disposed within said magazine and having their lower portions integral with said webs and normally diverged away from said front wall, said sides having rear ends adapted to be moved towards each other to stress said front wall and for shifting said rails towards each other, said webs and rails having longitudinally arranged and transversely aligned slots, a staple pusher having depending parts adapted to slidably straddle said rails to limit spreading of said rails away from each other for holding said rails and said sides substantially parallel to each other, and lugs carried by said parts and slidably guided in said slots.

2. In a stapling machine, a one piece sheet metal magazine adapted to contain staples and provided with a front wall, spaced sides having front ends integrally merged with and normally yieldingly diverging away from said front wall, spaced webs integral with the lower portions of said sides and spaced from said front wall, spaced upstanding rails disconnected from each other and spaced from said front wall to form staple guide means therewith and said rails being substantially parallel to and spaced from said sides and disposed within said magazine and having their lower portions integral with said webs and normally diverged away from said front wall, said sides except through said front wall being disconnected from each other and having rear ends adapted to be moved towards each other to stress said front wall and for shifting said rails towards each other, said webs and rails having longitudinally arranged and transversely aligned slots, a staple pusher movably seated on said rails and having depending parts adapted to slidably straddle said rails to limit spreading of said rails away from each other for holding said rails and said sides substantially parallel to each other, and lugs carried by said parts and slidably guided in said slots.

3. In a stapling machine, a one piece sheet metal magazine adapted to contain staples and provided with a front wall, rabbeted corner portions integral with and at the outer ends of and disposed rearwardly of said front wall and comprising shoulders disposed laterally of and spaced from said front wall, spaced sides except through said front wall and corner portions being disconnected from each other and having front ends integrally merged with the outer ends of said shoulders and said sides normally yieldingly diverging away from said front wall, spaced webs integral with the lower portions of said sides and spaced from said front wall, spaced upstanding rails disconnected from each other and substantially parallel to and spaced from said sides and disposed within said magazine and having their lower portions integral with said webs and normally diverged away from said front wall, said rails having front ends spaced from and between said shoulders and spaced from said front wall to form staple guide means, said sides having rear ends adapted to be moved towards each other to stress said front wall and for shifting said rails towards each other, said rails having longitudinally arranged and transversely aligned

slots, a staple pusher movably seated on said rails and having depending parts adapted to slidably straddle said rails to limit spreading of said rails away from each other for holding said rails and said sides substantially parallel to each other, and means carried by said parts and slidably guided in said slots.

4. In a stapling machine, a one piece sheet metal magazine adapted to contain staples and provided with a front transversely arranged wall, rabbeted corner portions integral with and at the outer ends of and disposed rearwardly of said front wall and comprising shoulders disposed laterally of and spaced from and to the rear of said front wall, spaced sides disconnected from each other except through said rabbeted portions and front wall 10 and having front ends integrally merged with the outer ends of said shoulders and said sides normally yieldingly diverging away from said front wall, spaced webs integral with the lower portions of said sides and spaced from said front wall, spaced upstanding rails disconnected from each other and substantially parallel to and spaced from said sides and disposed within said magazine and having their lower portions integral with said webs and normally diverged away from said front wall, said rails having front ends spaced from and between said shoulders and 15 spaced from said front wall to form staple guide means, said sides having rear ends adapted to be moved towards each other to stress said front wall and for shifting said rails towards each other, said rails having longitudinally arranged and transversely aligned slots, a staple pusher 20 movably seated on said rails and having depending parts adapted to slidably straddle said rails to limit spreading of said rails away from each other for holding said rails and said sides substantially parallel to each other, means carried by said parts and slidably guided in said slots, and spaced legs depending from the rear ends of said sides.

5. In a stapling machine, a base, a stanchion at the rear of and fixed to said base and having transversely spaced ears, a one piece sheet metal open top magazine adapted to contain staples and provided with a front wall and comprising spaced sides having front ends integrally merged with said front wall and rear ends straddling said ears, spaced webs integral with the lower portions of said sides and spaced from said front wall, spaced upstanding rails spaced from said front wall to form staple guide 40 means therewith and said rails being substantially parallel to and spaced from said sides and disposed within said magazine and having their lower portions integral with said webs, said rails having longitudinally arranged and transversely aligned slots, a staple pusher movably seated 45 on said rails and having depending parts slidably straddling said rails, means carried by said parts and slidably guided in said slots, fulcrum means traversing said ears and the rear ends of said sides for swingably holding said magazine relative to said base, a cap having a top wall and having spaced rear end portions straddling said sides and swingably retained on said fulcrum means; staple driving means comprising a flat spring having a reach within and secured to said top wall, an arcuate portion integral with said reach, a tail portion at the rear of and 50 integral with and offset relative to said arcuate portion, and a blade depending from the front end of said reach and provided with a gap; a cover plate bodily movable with said cap and below and spaced from said reach and having a rear end secured to said tail portion and including a front end having coating means in part projecting through said gap for slidably guiding said blade and including spaced bars removably receivable in said magazine through said open top and between said sides, a coiled sheave secured to said bars, a movable helical 55 spring interposed between said bars and trained over said sheave and including ends retained by said pusher and arcuate portion, and means to limit the reception of said bars between said sides.

6. In a stapling machine, a one piece open top sheet metal magazine adapted to contain staples and provided

with a front wall, rabbeted corner portions integral with and at the outer ends of said front wall and comprising shoulders extending laterally of and spaced from and to the rear of said front wall, spaced sides having front ends integrally merged with the outer ends of said shoulders, a cover plate having upwardly extending lugs at the front end thereof, flange means projecting forwardly of said lugs at the front ends thereof, a cap for said magazine, fulcrum means pivotally sustaining said cap relative to said sides; a relatively flat spring having a reach secured to said cap and upwardly spaced from said cover plate and having a rear portion offset relative to said reach and secured to the rear part of said plate, a staple driving blade depending from the front part of said reach; said flange means having means for slidably guiding said blade, and said flange means having means for cooperating with said shoulders to limit insertion of said cover plate through said open top and between said sides.

7. In a stapling machine, a one piece open top sheet metal magazine adapted to contain staples and provided with a front wall, rabbeted corner portions integral with and at the outer ends of said front wall and comprising shoulders extending laterally of and spaced from and to the rear of said front wall, spaced sides having front ends integrally merged with the outer ends of said shoulders, a cover plate having upwardly extending lugs at the front end thereof, flange means projecting forwardly of said lugs at the front ends thereof, a cap for said magazine, fulcrum means pivotally sustaining said cap relative to said sides; a relatively flat spring having a reach secured to said cap and spaced from said cover plate and having a rear portion offset relative to said reach and secured to the rear part of said plate, an arcuate portion interconnecting said reach and rear portion, a staple driving blade depending from the front part of said reach and including spaced limbs defining a slot; said flange means cooperating with said shoulders to limit insertion of said cover plate through said open top and between said sides, a lip extending from said

plate and disposed below said flange means to facilitate guiding of said blade, and means carried by said flange means and in part projecting into said slot to movably retain said blade against said lip.

- 5 8. In a stapling machine, a one piece open top sheet metal magazine adapted to contain staples and provided with a front wall, rabbeted corner portions integral with and at the outer ends of said front wall and comprising shoulders extending laterally of and spaced from and to the rear of said front wall, spaced sides having front ends integrally merged with the outer ends of said shoulders, a cover plate having spaced bars and having upwardly extending lugs at the front ends of said bars, flange means projecting forwardly of said lugs at the 10 front ends thereof, a cap for said magazine, fulcrum means pivotally sustaining said cap relative to said sides; a relatively flat spring having a reach secured to said cap and spaced from said bars and having a rear portion offset relative to said reach and secured to the rear part of said plate, a downwardly curved portion interconnecting said reach and rear portion, a staple driving blade depending from the front part of said reach and including spaced limbs defining a slot; said flange means having means straddling said blade to slidably guide the latter, 15 20 said flange means having means for cooperating with said shoulders to limit insertion of said bars through said open top and between said sides, a lip substantially at the level of said bars to facilitate guiding of said blade, and a T-shaped lug in part projecting through said slot 25 for slidably retaining said blade against said flange means and lip, and projections carried by said sides to support the rear end of said cover plate.
